UNITED STATES PATENT OFFICE.

THOMAS GRISWOLD, JR., OF MIDLAND, MICHIGAN, ASSIGNOR TO THE DOW CHEMICAL COMPANY, OF MIDLAND, MICHIGAN, A CORPORATION OF MICHIGAN.

METHOD OF AND APPARATUS FOR DRY CLEANING.

Application filed November 2, 1921. Serial No. 512,242.

To all whom it may concern:

Be it known that I, THOMAS GRISWOLD, Jr., a citizen of the United States, and a resident of Midland, county of Midland, 5 and State of Michigan, have invented a new and useful Improvement in Methods of and Apparatus for Dry Cleaning, of which the following is a specification, the principle of the invention being herein explained, and 10 the best mode in which I have contemplated applying that principle, so as to distinguish it from other inventions.

The present improvements have to do more particularly with the removal from 15 garments, such as underwear, stockings and the like, of the occasional oil spots which appear to be unavoidable in the course of fabrication. It will be understood, however, that use of the invention is not limited 20 to factories making garments, but may be employed generally wherever materials of the character in hand are found with limited areas required to be cleaned and where it is not necessary or desirable to cleanse the 25 entire article.

The current practice, in underwear factories for example, is to throw out the garments on which spots are detected and wash 30 such spots with gasoline and soap preparations, using water and hand labor. This procedure necessitates that the garments be subsequently dried on a stretcher and ironed, thus requiring considerable time and constituting a serious item of expense in fabrication. 35 An even more serious objection to such current procedure is the disarrangement of the course of manufacture, in that it is usually regarded as necessary that the soiled garments be restored to the particular 40 lot and package to which they belong so that sizes, lots and costs may be accurately kept. Accordingly, the delay in thus removing the oil spots holds up the progress of the whole lot of goods and requires that 45 after such spots have been removed the goods must be restored at a particular point in the line of progress of the lot.

The present invention, in the first place, has as its object the provision of means 50 whereby a solvent, such as carbon tetrachloride may be employed in such an economical manner as to render its use commercially practicable, while inasmuch as

such solvent readily evaporates, the goods treated therewith will not require re-stretching or ironing, and the time for performing the cleaning operation may be made so short that such goods can be promptly returned to their original positions in the line of progress of the material through the factory. Instead of carbon tetrachloride other equivalent cleansing agents may be employed, and particularly a mixture of solvents with carbon tetrachloride as one of the ingredients. Such a mixture may contain, 65 for example, in addition to carbon tetrachloride, either acetone, or acetone and benzol. The use of carbon tetrachloride is highly desirable because it enables the cleaning operation to be carried on in a room or 70 factory in which inflammables, such as garments, are present in quantity without fire hazard, which obviously is not the case where naphtha or other inflammable solvents are used. Furthermore, by reason of the 75 method and special construction of apparatus which I have devised the quantity of solvent carried out by the goods is so small and the exposure of the stock of solvent used in the device is so limited that but 80 little odor is present in the room, and a minimum of inconvenience is entailed as regards the operator.

A further difficulty encountered in prevailing methods of cleaning spots from garments is the so-called "ringing" of the spot, i. e., a discoloration or ring is left around the spot after cleaning. This is apparently due to the capillary action of the fabric which causes the solvent to spread, carrying 85 with it the oil which constituted the original spot, and upon evaporation of such solvent, while such original spot may have been removed, the result is the production of a larger and more unsatisfactory defect. By 90 my present improved method and apparatus I am enabled to avoid this "ringing" effect in that I introduce the solvent to the goods around the spot in a circle and take it 95 out in the spot, thereby preventing the flow 100 of a solvent containing oil from the spot outwards into the garment.

To the accomplishment of the foregoing and related ends, the invention then consists of the steps and means hereinafter 105 fully described and particularly pointed out

in the claims; the annexed drawings and the following description setting forth in detail certain means and one mode of carrying out the invention, such disclosed means and mode illustrating, however, but one of various ways in which the principle of the invention may be used.

In said annexed drawings:—

- Fig. 1 is a side elevation of an apparatus 10 adapted for the carrying out of my improved method of dry-cleaning; Fig. 2 is a front elevation of such machine; Fig. 3 is a plan view thereof; Fig. 4 is a central vertical section of a portion of such apparatus 15 taken on a somewhat larger scale, the plane of the section being indicated by the line 4—4, Figs. 2 and 3; Fig. 5 is a broken view similar to Fig. 4, but showing on a still larger scale the construction of two co-operating parts; Fig. 6 is a transverse section of certain of the parts appearing in Fig. 4, the plane of the section being indicated by the line 6—6 on said figure; and Fig. 7 is a sectional view similar to Fig. 4 20 but showing only one portion of the apparatus therein appearing in modified form.

The apparatus as illustrated in the aforesaid drawings is supported upon a suitable table or bench 1 which may take on any desired form. Supported in the lower framework of the table is a motor 2 that serves to drive a countershaft 3 through the medium of suitable pulleys 4 and 5 and connecting belt 6, such shaft being hung from the under side of the table top. From such table top is also hung a tank or reservoir 7 for containing a quantity of a solvent used in the cleaning operation, such reservoir being provided with a filling nozzle 8 and a draw-off 9 for the sediment or the spent charge. Leading from this reservoir is a pipe 10, in which is interposed a strainer 11 and a suitable pump 12, shown as a standard geared oil pump, by means of which the solvent may be withdrawn and supplied to the cleaning apparatus proper through suitable connections, as will be presently explained. The pump 12 is driven from a pulley on countershaft 3 through a belt 13, 45 as will be readily understood.

The cleaning apparatus proper comprises a hollow member or pipe 15 of inverted U-shape, which may be referred to inclusively as a goose neck, such member being pivotally attached to the top of the table near the forward edge thereof between two standards 17 by means of a pin 16. Such goose neck member is formed with a depending arm 18 that projects through the table top, and is connected by means of a link 19 with a foot pedal 20, the effect of depressing such pedal being to swing the goose neck member in a counter-clockwise direction and bring its free end forcibly down upon a cup member 21 mounted di-

rectly at the edge of the table top 1. A tension spring 22, connected at one end to the under side of the table top, and at the other adjustably connected with link 19, serves normally to retain the goose neck in the raised position shown in dotted outline in Fig. 4, in which the front end is lifted clear of said cup member.

Hinged upon the same pin 16, about which the goose neck 15 is thus oscillatory, 75 is a hammer 25, which, together with the curved supporting arm 26 therefor, is wholly contained within the goose neck. Said arm 26 is provided with a lever extension 27 that depends below the pin 16 and 80 is connected, by means of a link 28, with an eccentric shaft 29 journaled in the rear depending portion 30 of the goose neck. This eccentric shaft 29 is driven by means of a belt 31 passing around a pulley 32 on one of its ends which projects through the side wall of the goose neck, the other end of such belt passing around a pulley 33 on countershaft 3. The effect of rotating eccentric shaft 29 is to cause the arm 26 to 90 vibrate and thereby raise and lower the hammer in an approximately vertical direction, the raised position thereof being shown in dotted outline, and the lowered position in full lines in Fig. 4.

It will be noted that oscillation of the goose neck does not in any way change the relation between the pin 16, the hammer arm 26, connecting rod 28 and eccentric shaft 29, all of which maintain their positions relative to such goose neck, unaffected by the movement of the latter.

The cup 21, which, for convenience of illustration, is shown in Fig. 4 as rotated through an angle of 90 degrees from its proper position, as shown in Figs. 2 and 3 for example, has a washer or gasket 35 in its upper end that is retained in place by a suitable shoulder 36 and serves to form a tight seal with the free end of the goose neck 15 in the lowered position of the latter. This cup is divided into two chambers by a partition 37, one such chamber being connected with a pipe 38 and the other with a pipe 39, which pipes are connected in turn with the reservoir 7 and pump 12 so that a circulation of solvent may be set up from said reservoir through pipe 39, the one chamber 40, the other chamber 41 and thence out pipe 38.

Within the cup 21, supported upon the partition 37, and resting in a suitable seat therein, is an annular member 42 that carries at its upper end a plate 43. Said plate, as best shown in Fig. 5, is perforated and lies immediately below and closely adjacent to the perforated lower surface of the hammer head 25. With the parts properly positioned the vibratory movement imparted to the arm 26 will, when the goose neck is

pressed down against the cup, cause said hammer 25 to strike upon said plate 43 as upon an anvil.

In order to provide for adjustment between such hammer head and anvil the eccentric shaft 29, in the rear end of the goose neck, is preferably journaled in eccentric bushings 50, as shown in detail in Fig. 6, which bushings project beyond the goose neck on either side and are clamped into an adjusting yoke 51. The latter carries a screw 52 that is adapted to enter any one of a series of recesses 53 provided upon the outer cylindrical surface of the rear end of the goose neck. By shifting the position of such yoke, and correspondingly rocking the eccentric bushings 50 to which it is attached, the normal or mean position of the hammer arm 26 within the goose neck may be raised or lowered, as will be evident, and as a result the normal position of the hammer head 25 can be varied so as to affect its relation to the anvil plate 43. When a satisfactory adjustment is secured, by tightening screw 52 the yoke is secured in position and thereafter maintains the hammer head in the adjusted relation selected with respect to the anvil.

Pipe 39, leading to the cup, connects through a cross valve 55 with the portion of pipe 10 rising from pump 12 and with a by-pass 56 that joins pipe 38 at the T 57 and returns to the reservoir through a connection 58. In the by-pass 56 there is located a throttle valve 59, and connected with the riser 10 is a gauge 60, shown simply as a glass tube, such gauge being a convenience, although not necessary to the operation of the apparatus. In pipe 39 there is provided a quick-opening valve 61 that is adapted to be operated from a hand lever 62 through the medium of a bell-crank arm 63 carried by said lever and a link 64 that connects said arm with an arm 65 on the valve stem. Hand lever 62 is pivotally supported on a bracket 66 depending below the table top 2 and carries a pulley 67 that is disposed to engage with the belt 31 and act as a belt tightener therefor.

The operation of the several component parts of the apparatus, having been indicated in connection with the description thereof, the general manner of operation of the apparatus will now be set forth.

The countershaft 3 will be operated at a predetermined rate of speed from motor 2 or other source of power. Assuming, then, that the foot lever 20 is released and the goose neck 15 accordingly raised, a garment or like article having a spot thereon to be removed by means of the solvent contained in the reservoir 7 may be placed in position between the cup 21 and the lower end of the goose neck with such spot over

the anvil plate 43. The cross valve 55 and the by-pass valve 59 will be so adjusted that when the quick-opening valve 61 is open the flow of solvent induced by the pump 12 will be divided between pipe 39 70 and the by-pass 56 that returns to the reservoir through connection 58. By proper manipulation of the valves in question the amount of solvent which is supplied to the cup 21 will be just sufficient to cause a certain small desired rate of flow of solvent up through the outer annular chamber 40, and over the plate 43, through which it will drain into the interior of the anvil and thence return by way of chamber 41 in the 80 cup and the pipe 38 back to the reservoir.

With the proper rate of flow of solvent over the anvil plate thus established, and the goose neck raised as before stated, the hand lever 62 is manipulated to stop the flow of solvent to the cup by way of pipe 39. An aperture 70, not previously referred to, may be provided in the side of the annular member 42, so that as soon as the flow of fresh solvent is stopped, the excess 90 solvent above such aperture immediately drains out of the cup, returning by way of pipe 38 to the reservoir. The garment or other article having been slipped in between the goose neck and the cup, and the spot centered upon the anvil as previously described, the goose neck is thereupon lowered by pressing down the foot lever 20 until the garment is firmly clamped against the cushioned mouth-piece of the cup. 100 Thereupon the lever 62 is drawn forwardly so as to open valve 61 and admit the solvent to the cup at predetermined rate of flow. At the same time the tightener pulley 67 is brought into play to tighten belt 31 and thereby cause the eccentric shaft 29 to rotate, this in turn vibrating the lever arm 26 and causing the hammer head 25 to beat upon the portion of the garment centered over the anvil 43.

The solvent, as it wells up in the outer annular chamber of the cup, surrounds the spot which is to be removed as the latter rests upon the anvil, and flows from a ring around such spot to and through the same into the central opening in annular member 42, and thence to the cup exit. The result of the action of the hammer is to alternately compress and permit expansion of the fibrous material composing the garment, and at the same time it assists in the mechanical removal of any solid or insoluble form of dirt that may adhere to the oil moistened fibers of the fabric. The solvent flow will carry away such oil by solution, and such loosened solid particles in suspension, so that after a few moments' treatment the lever 62 may be moved to the rear, thereby closing the valve 61 and stopping the further flow of solvent to the cup. 130

Meanwhile the goose neck is maintained closed by continuous pressure on foot lever 20 until the greater part of the solvent in the wetted portion of the garment within 5 the goose neck is drained away. Thereupon the foot pressure may be released, the goose neck opened, and the garment removed.

If it be desired to continue the action of the hammer after the flow of solvent has 10 ceased the idler pulley 67 may be removed and the belt 31 made tight enough so that the eccentric shaft 29 will be driven irrespective of the movement of said hand lever.

While the action of the hammer has been 15 found of assistance, particularly in expediting the cleaning operation without requiring the flow of solvent to be at a very high rate, such hammer may be entirely dispensed with, as illustrated in the modified 20 construction of Fig. 7. As here shown, while I have retained cup 21 in form substantially identical with that shown in Fig. 4, the lower end of the goose neck 15 is simply 25 closed across by means of a partition 71 spaced a short distance back so as to leave a space or chamber 72 above the anvil plate 43 and the fabric resting thereon, when the goose neck is pressed down on the cup. In order to press the fabric closely against the 30 plate 43 around the outer edge thereof, an annular plate 73 may in addition be provided, being attached to the partition 71 through the medium of a spiral spring 74. As a result, when the goose neck is brought 35 down on the cup, the fabric is not only held upon the gasket 35 by pressure of the end of the goose neck itself, but upon the anvil proper, by the pressure of such ring 73. This compels the solvent to flow up through 40 the fabric around the outside and down through the interior areas over the perforated plate without by-passing underneath the fabric. With this arrangement the rate 45 of flow of the solvent can be increased, and such extra flow is found to be the equivalent, to a large extent, of the action of the vibrator hammer with a lower rate of flow of solvent.

In both forms of apparatus the trouble- 50 some "ringing" of the spot is practically entirely avoided because fresh solvent always comes in through the fabric around the original spot and washes towards the latter and not away from it. By enclosing the 55 portion of the fabric which is to be treated within a sealed compartment, such as is formed by the goose neck and the cup, excessive use of solvent and waste by evaporation are avoided, and at the same time the 60 clamping of the fabric between the free end of the goose neck and the cushion seal provided on the cup prevents almost entirely the spread of the solvent by capillarity beyond the circular area so enclosed. The amount of solvent that remains in the fab-

ric after cleaning is accordingly limited to that which remains absorbed in such relatively small portion.

It will be understood of course that the solvent may be heated in certain cases if 70 found desirable in order to facilitate the removal of spots, since the opportunity for the solvent to evaporate is so circumscribed, in the present apparatus. It will also be understood that when the solvent in the reservoir becomes contaminated with oil or dirt to a degree that will cause unsatisfactory cleaning it may be drawn off and a fresh charge put in; or the settling in the 75 bottom of the reservoir may be drawn off from time to time and fresh solvent supplied to make up for what is thus drawn off plus that which is lost in the process. While various changes may be made in the apparatus hereinbefore described, either by way 80 of further simplifying same or rendering the operation more nearly automatic, it will be noted that the arrangement as shown in the drawings and explained above permits the operator to use both hands in placing the 85 garment or article to be cleaned between the cup and the goose neck, and that after such garment has been clamped between the two parts in question the operator's hands are 90 free to manipulate the other parts of the 95 mechanism.

It will also be understood that the establishment of a ring-shaped barrier surrounding the portion of the fabric, or like material being treated, may be accomplished in 100 other ways than by reversely flowing the solvent, or equivalent cleansing medium through such surrounding and spotted portions. Thus, a sufficient flow of solvent all 105 in one direction through a circumscribed area, including both portions, may be maintained so as to establish in effect such a ring-shaped barrier of fresh solvent and prevent diffusion of the contaminated solvent passing through the affected portion of such 110 area.

Other modes of applying the principle of my invention may be employed instead of the one explained, change being made as regards the means and the steps herein disclosed, provided those stated by any of the following claims or their equivalents be employed.

I therefore particularly point out and distinctly claim as my invention:—

1. In a method of removing a spot from a fabric or like material, the step which consists in passing a directed current of solvent through and thence away out of contact with a definitely circumscribed portion of such material, including the spot and the material immediately surrounding the same.

2. In a method of removing a spot from a fabric or like material, the step which consists in passing a directed current of solvent

- through and thence away out of contact with a limited portion of such material, including the spot, and at the same time protecting such portion and the solvent passing therethrough from the atmosphere. 5
3. In a method of removing a spot from a fabric or like permeable material, the step which consists in passing a directed current of a cleansing medium through and thence 10 away out of contact with a limited portion of such material, including the spot, thereby establishing a flowing directed barrier of such medium around the spot and preventing soiling matter removed from the spot 15 from passing outwardly therefrom into the fabric.
4. In a method of removing spots from a fabric or like material, the steps which consist in flowing a solvent through a circumscribed portion of such material including such a spot and simultaneously beating the spotted portion. 20
5. In a method of removing a spot from a fabric or like material, the step which consists in passing a directed flow of solvent through and around the spot at a rate which will prevent soiling matter removed by the solvent from moving outwardly from the spot into the fabric, thereby preventing 25 ringing. 30
6. In a method of removing spots from a fabric or like material, the steps which consist in flowing a solvent through such spot, and simultaneously flowing fresh solvent through the portion of such material surrounding such spot, so as to prevent diffusion of the contaminated solvent into such 35 surrounding portion. 40
7. In a method of removing a spot from a fabric or like material, the steps which consist in passing a directed current of solvent through the spot and simultaneously passing a directed current through a portion of the material surrounding the spot, whereby 45 the soiling matter removed from the fabric by the solvent is prevented from passing outwardly from the spot into the fabric surrounding the treated area. 50
8. In a method of removing a spot from a fabric or like material, the steps which consist in washing the spot in a flow of solvent and maintaining at the same time a flow of solvent through a portion of the material surrounding the spot in volumes sufficient to 55 prevent matter taken up by the solvent passing through such spot from passing outwardly therefrom through the solvent or material into the adjacent portion of the latter. 60
9. In a method of removing spots from a fabric or like material, the steps which consist in flowing a solvent through such spot, preventing diffusion of the contaminated solvent into such surrounding portion, and simultaneously beating the spotted portion. 65
10. In a method of cleaning a fabric or like permeable material, the step which consists in flowing a cleansing medium successively through adjacent portions of such material in opposite directions. 70
11. In a method of cleaning a fabric or like permeable material, the step which consists in flowing a cleansing medium successively through a portion of such material surrounding the portion to be cleaned and then through such last-mentioned portion. 75
12. In a method of cleaning a fabric or like permeable material, the step which consists in flowing a cleansing medium successively through a portion of such material surrounding the portion to be cleaned and then in the opposite direction through such last-mentioned portion. 80
13. In a method of removing spots from a fabric or like permeable material, the step which consists in flowing a cleansing medium successively through a circular portion of such material surrounding such a spot and then through the latter in the opposite direction. 85
14. In a method of removing spots from a fabric or like permeable material, the steps which consist in flowing a cleansing medium successively through a portion of such material surrounding the affected area and through such area itself, and simultaneously establishing a barrier against diffusion of the resulting contaminated solvent into the surrounding portion of such material. 90
15. In an apparatus of the character described, the combination of separable members adapted to clamp therebetween a circumscribed area of a piece of fabric or like permeable material, said members being chambered to permit the circulation of a solvent medium in opposite directions through the enclosed area of such material. 100
16. In an apparatus of the character described, the combination of separable members adapted to clamp therebetween a circumscribed area of a piece of fabric or like permeable material, said members being chambered to permit the circulation of a solvent medium successively through different portions of the area of such material thus enclosed. 105
17. In an apparatus of the character described, the combination of separable members adapted to clamp therebetween a circumscribed area of a piece of fabric or like permeable material, said members being chambered to permit the circulation of a solvent medium successively through an outer portion of the area of such material thus enclosed and through the central portion 110 surrounded by such outer portion. 120
18. In an apparatus of the character described, the combination of a cup-member, a member adapted to press a piece of fabric or like permeable material against said cup- 130

- member, a partition in the latter forming outer annular and central chambers, and means adapted to circulate a solvent medium through such chambers in succession.
- 5 19. In an apparatus of the character described, the combination of a cup-member, a member adapted to press a piece of fabric or like permeable material against said cup-member, a partition in the latter forming 10 outer annular and central chambers, and means adapted to circulate a solvent medium upwardly through such outer chamber and then downwardly through such central chamber.
- 15 20. In an apparatus of the character described, the combination of a cup-member, a member adapted to press a piece of fabric or like permeable material against said cup-member, a partition in the latter forming 20 outer annular and central chambers, a perforated plate at the upper end of such central chamber, a vibrating hammer co-operative therewith, and means adapted to circulate a solvent medium upwardly through 25 such outer chamber and then downwardly through such central chamber.
21. In an apparatus of the character described, the combination of a cup-member, a relatively movable hollow member having 30 an open end adapted to co-operate with said cup-member to clamp thereagainst a piece of fabric or like permeable material, a partition in said cup-member forming outer annular and central chambers, and means adapted to 35 circulate a solvent medium through such chambers in succession.
22. In an apparatus of the character described, the combination of a cup-member, a relatively movable hollow member having 40 an open end adapted to co-operate with said cup-member to clamp thereagainst a piece of fabric or like permeable material, a partition in said cup-member forming outer annular and central chambers, a perforated 45 plate at the upper end of such central chambers, a vibratory hammer within said hollow
- member co-operative with said plate, and means adapted to circulate a solvent medium upwardly through such outer chamber and then downwardly through such central 50 chamber.
23. In an apparatus of the character described, the combination of a cup-member, a curved, hollow member having one end open and oscillatory about its other end to 55 move such open end towards said cup-member to clamp thereagainst a piece of fabric or like permeable material, a partition in said cup-member forming outer annular and central chambers, a perforated plate at the 60 upper end of such central chamber, a vibrating hammer within said hollow member co-operative with said plate, and means adapted to circulate a solvent medium upwardly through such outer chamber and then downwardly through such central chamber. 65
24. In an apparatus of the character described, the combination of separable members adapted to clamp therebetween a piece of fabric or like permeable material, said members being chambered to permit the circulation of a solvent medium in opposite directions through the enclosed area of such material, and regulable means for establishing such flow of solvent at predetermined 70 rate.
25. In an apparatus of the character described, the combination of separable members adapted to clamp therebetween a piece of fabric or like permeable material, said members being chambered to permit the circulation of a solvent medium through the enclosed area of such material, and regulable means for establishing such flow of solvent at predetermined rate, said means including 75 a storage tank, a circulating pump, a supply pipe leading from said pump to one such chamber, a return pipe leading from the other such chamber to said tank, and a bypass from said first-named pipe to said tank. 80
- Signed by me this 29 day of October, 1921.
- THOMAS GRISWOLD, JR.
